UNITED STATES PATENT OFFICE

FRANK WOLF, OF NEW YORK, N. Y.

ACCESSORY FOR COLLAPSIBLE TUBES

Application filed January 17, 1931. Serial No. 509,314.

My present invention relates to accessories for collapsible containers, and has for its general object the provision of an improved top for such containers, the invention being 5 in the nature of a novel attachment produced especially for use in connection with collapsible tubes of the kind commonly employed for containing tooth paste, shaving cream, cold cream and other substances, although it is to be understood that in practice the attachment of my invention is not confined in its use to such particular kind of container.

An object of the invention is the provision 15 of an improved attachment having improved means whereby operatively to carry a cap for closing the discharge nozzle or spout of the tube.

Another object of the invention is the provision 20 of an accessory of the kind described, in which the cap closure, for ready connection with and disconnection from the screw threads of the nozzle, will be guided along a path or line coaxial with the nozzle itself, and, in conjunction with this feature, to so support the closure that it can be swung aside when paste is to be ejected from the nozzle.

It is also within the province of the present invention to provide an accessory of the 30 character described which may be produced for use on the tube either with or without a stand for the tube; and further to provide a construction which, as a manufactured article, may be produced either with or without 35 a closure for the nozzle.

Where the accessory is produced without a closure for the nozzle, its construction is such that the original cap closure accompanying a tube may be appropriated and applied 40 to the accessory for use as a permanent part thereof during the life of that particular tube, and then discarded, if desired, when the tube is discarded.

With the foregoing and other objects in 45 view, the invention consists in the improved accessory, and in the form, construction, and relative arrangement of parts, as will be hereinafter more fully described and claimed.

In the accompanying drawing, wherein I 50 have illustrated several simple and practical

embodiments of the invention as reduced to practice, and in which similar reference characters designate corresponding parts throughout the several views:—

Figure 1 represents a central, vertical, sectional view through an accessory made in accordance with my invention, illustrating the same as applied to a collapsible tube furnished with a stand, both the tube and stand being fractionally shown; 55

Fig. 2 is an elevational view of the parts shown in Fig. 1;

Fig. 3 is a fragmentary sectional view of the accessory upon a tube, this view showing the cover flange constructed for contacting 65 the bead flange of the tube;

Fig. 3a is a fragmentary sectional view showing a threaded connection between the cap pin and the supporting arm.

Fig. 4 is a view similar to Fig. 1, but showing a modified construction which provides for the utilization of the original cap of the tube as a part of the accessory; 70

Fig. 5 is a top plan view of the parts shown in Fig. 4; and 75

Fig. 6 is a fragmentary sectional detail, showing the cap produced with a groove in which to seat the loop of the holder arm.

Referring now with more particularity to the accompanying drawing, the reference 80 character 10 designates on a somewhat enlarged scale the upper part of a collapsible tube of the kind commonly employed for containing tooth paste, cold cream, shaving cream, and the like; and this tube is provided in the usual way with a comparatively rigid top 11 having a bead flange 12 at its lower edge and also having a central outwardly projecting nozzle or neck 13 which is exteriorly screw-threaded for receiving the 85 usual end cap or closure.

The accessory of my present invention includes a main member in the form of a cover 14, shaped to fit upon the top 11 and having a central aperture 15 for the projection therethrough of the screw-threaded nozzle. Projecting upwardly from the cover adjacent its rim are a pair of spaced lugs 16, the inner ends of which are joined by an upstanding abutment or stop member 17. A holder in 100

the form of an angular arm 18 has the end portion 19 thereof positioned between the lugs 16 and mounted therebetween for swinging movement upon a pivot pin 20 which connects said lugs. Said arm portion 19 has a cam face 21 which is adapted to fit flatly against the abutment 17 when the arm is in elevated position as shown in Fig. 1; and the opposite end of said arm has a portion 22 which lies in a plane substantially at right angles to the cam face 21. The arm portion 22 is produced with a head 23 having a bearing 24 wherein an axis pin 25 is mounted to have both axial and turning movement. 26 15 denotes a cap or closure for the nozzle, this cap consisting of a head portion 27 and a tubular body or shank portion 28 which is interiorly threaded for engagement with the screw threads of the nozzle. The head of the 20 cap is united at a central point with the end of the axis pin 25; and the free end 29 of the shank or body 28 constitutes an abutment which is adapted to engage the cover around the nozzle. Under this arrangement, when 25 the arm is in elevated position as shown in full lines in Fig. 1, with the cam face 21 in engagement with the stop 17, the cap is sustained in adjoining coaxial relation with the nozzle; and the cap, during its screw-threaded application to or its disconnection from the nozzle, is held in such relative position and guided by the axis pin which is fitted in the head for both axial and turning movements. As the cap is screw-threaded upon 30 the nozzle its abutment end 29 engages the cover so as to bind the cover to the top of the tube for the support of the tube, if desired, by the cover. Preferably and as shown, the head of the cap is provided with an interior sealing projection 30 which is adapted 35 to fit snugly within the interior of the nozzle. Upon unthreading the cap from the nozzle, the arm can be swung outwardly into the position shown by the broken lines in 40 Fig. 1, where it will be clear of the nozzle in order to permit the discharge of the contents of the tube. The arm portion 19 is also provided with a cam face 31 for engagement with the stop or abutment 17 whereby to limit 45 the outward movement of the arm and sustain it in the desired position. Instead of the axis pin 25 having sliding and turning fit in the bearing 24 as herein represented, it may be screw-threaded through the bearing 50 for axial adjustment therein, and in such case, the pin 25 on rotation would turn cap 26, as when the cap 26 is rotated it would turn pin 25 in its bearing 24. An example 55 of this construction is illustrated in Fig. 3a, in which it will be seen that the pin 25 and bearing head 23 are provided respectively with cooperating screw threads 25' and 25''. The advantage of this construction is that, 60 upon unscrewing the cap from the nozzle, the pin, because of its screw-threaded engage-

ment with the bearing head, cannot slip axially in the bearing head, but to the contrary will be positively held at the position necessary for the re-engagement of the cap with the nozzle. 70

In the embodiment shown in Figs. 1 and 2, the cover is represented as provided with a flange 32 for cooperation with a pair of leg members 33 which may constitute part of a stand or holder for supporting the collapsible tube. These leg members are represented as having at their upper ends transverse portions 34 shaped to engage under the bead flange 12 and also against the body of the tube. The cover with its flange 32 may be 75 made so that the flange will engage the transverse portions 34 and bind the same in engagement with the bead flange. Means 80 may also be furnished for detachably connecting the cover flange to the leg members; and in the present instance the means to this end are represented as comprising oppositely disposed bayonet slots 35 in the flange 32 and suitable cooperating pins 36 which project 85 from the leg members. The cover of my improved accessory may, however, be made in such size that its flange 32 will directly engage the bead flange 12 of the tube top as shown in the fragmentary detail section illustrated 90 in Fig. 3. Therefore, in carrying out my invention, a stand or similar holder for the collapsible tube is not an essential, since the cover can be firmly bound to the top of the tube by screw-threading the cap tightly upon 95 the nozzle as hereinbefore described. 100

In the illustrative embodiment shown in Figs. 4 and 5, the arm for the cap comprises a resilient wire member having one end portion looped upon itself to provide a bearing 37 whereby to turn the arm upon the pivot 105 pin 38. A suitable pair of lugs 39, upstanding from the cover 40 carries the pivot pin 38. The opposite end of the wire arm is made into a resilient circular loop 41, forming thereby 110 an open socket adapted to receive the body or shank portion 42 of a headed cap 43. Between the circular loop 41 and the bearing part 37, this wire arm is formed with a resilient elongated loop 44, of which the portion 45 which constitutes the connection with the circular loop 41 is relatively longer than the portion 46 which constitutes the connection with the bearing part 37. Under this construction, the portion 45 may be moved 115 outwardly with respect to the portion 46 so that the cap may be moved into a position in adjoining coaxial relation to the nozzle when the cap is to be screw-threaded upon the nozzle, it being evident of course that the body of the cap has turning fit in the resilient circular loop 41 in order that the screw-threaded operation may be effected. Owing to the shape of the resilient wire arm and particularly to the provision of the elongated loop 44, the cap is maintained, both for its appli- 120 125 130 135

cation and removal, in proper coaxial relation to the nozzle. With this construction, as the cap is threaded upon the nozzle, the resilient arm 45 may be tensioned toward the arm 46 and the relationship of the arm 45 to the arm 46 and the pivot 38 is such that no impedance is created by the arm 45 to the straight line movement of cap 42 when screwed onto or off the threaded nozzle of the collapsible tube 10, the arm 45 partaking of a substantially vertical movement, since the arc formed by the movement of the arm 45 away from the top of the tube is very large. The resiliency of arm 45 enables the cap 42 to work in a straight line direction when the cap engages the thread of the nozzle 13. The cap, upon being unthreaded from the nozzle, may be swung aside by swinging the wire arm upon its pivotal connection, the end 47 of the wire arm being projected from the bearing 37 so as to provide a stop for limiting the outward swing of the arm.

In connection with the form of construction shown in Fig. 4, I have illustrated wire legs 48 having at their top ends transverse portions 49 which are adapted to engage the opposite sides of the tube and at the same time to engage under the bead flange 12 thereof. The flange 50 of the cover 40 may be produced with an inward deformation 51 which is adapted to engage over the curved peripheries of the transverse leg portions 49. Where this type of accessory is employed without leg portions, the cap may be utilized as means for binding the cover to the top of the tube so as to support the tube by the cover, as in the form of construction first above described. It will be evident that any suitable means may be provided whereby 40 positively to maintain the cap for rotation in the circular loop 41. One convenient method of providing such positive operative connection is illustrated in Fig. 6, in which I show the body or shank 42 of the cap as provided with an annular groove or seat 52 for receiving the circular loop 41 therein, such annular groove preferably being provided adjoining the overhanging shoulder 53 of the head.

50 In accordance with the form of construction illustrated in Figs. 1 and 2, the accessory is produced as an article of manufacture with a cap or closure forming a part thereof. In this case, the threaded body or shank 53 of the cap is produced in a standard form so as to fit the standard type of nozzle for which it is intended. In accordance with the form of construction illustrated in Figs. 4 and 5, the accessory may be produced as an article of manufacture without any cap at all; since in this form of the device, the cap or closure which accompanies the collapsible tube may be put in the circular loop so as to become a part of the accessory for use in connection with the tube. In this case, when it is de-

sired to discard the tube after using the contents thereof, the cap may also be discarded, since a new cap is always furnished with the new tube.

It is in place to note here that the types of accessories herein disclosed not only provide means for sustaining the cap in a position for quick application to or removal from the nozzle, but also constitute a sanitary measure, since the cap upon detachment from the nozzle cannot be dropped upon the floor or into a sink where it is likely to be contaminated.

Each of the forms of construction herein disclosed evidences in its simplest form a sustaining and guiding means for the cap or closure by means of which the cap for its quick application and as well for its quick removal is sustained in proper coaxial relation to the nozzle, with the result that the threads of the cap and nozzle readily cooperate and especially that the threads of the nozzle, which are more or less soft, are not deformed and destroyed in applying and removing the cap. The device of my accessory, therefore, provides simple and practical means whereby to maintain the contents of the tube in good condition, for with the threads of the nozzle maintained in good condition and with the cap properly threaded upon the nozzle a tight air seal is effected which prevents hardening or coagulation of the contents of the tube within the nozzle.

While my improvements have been illustrated and described with some degree of particularity, it is realized that in practice various changes and alterations may be made therein. It has been sought herein to illustrate only such embodiments as will suffice to exhibit the character of the invention. Reservation is, therefore, made to the right or privilege of changing the form of the details of the construction or otherwise altering the arrangement of parts without departing from the spirit of the invention or the scope of the appended claims.

I claim:—

1. An accessory for collapsible tubes having a top end with a threaded outlet nozzle, said accessory comprising a main member shaped to overlie the top end of the tube, a holder device connected with said main member for relative movement with respect thereto, a cap threaded for engagement with the nozzle rotatably carried by the holder device, and adapted to be turned relatively with respect to the holder device and to the main member for engagement with and disengagement from the nozzle, said holder device being adapted, when in one position, to sustain and guide the cap in coaxial relation to said nozzle, for the application of the cap in such relation and for its removal.

2. An accessory for collapsible tubes having a top end with a threaded outlet nozzle,

said accessory comprising a main member adapted to overlie the top end of the tube, a cap threaded for threaded engagement with the nozzle, a device relatively movable on the main member supporting the cap thereto, said device supporting the cap for rotary movement with respect thereto and for independent axial movement with respect to the main member, and a stop for the device arranged for engagement thereby in a position in which the device will sustain the cap in adjoining coaxial relation to the nozzle whereby the cap through its axial movement may be engaged with and disengaged from the nozzle.

3. In combination with a collapsible tube having a comparatively rigid top and a projecting exteriorly threaded outlet nozzle, a cover shaped to fit the top around the nozzle, a holder attached to the cover for swinging movement, a cap carried by the holder for turning movement and threaded for engagement with the threads of the nozzle, and an abutment end provided on the cap for engagement with the cover around the nozzle so as to bind the cover to the top when the cap is tightened upon the nozzle.

4. An accessory for collapsible tubes having a comparatively rigid top and a projecting screw-threaded outlet nozzle, said accessory comprising a cover shaped to fit the top, an arm pivoted to the cover for swinging movement and provided with a bearing head, an axis pin mounted in the bearing head for axial movement with respect thereto and relatively to the cover, and a cap carried by the axis pin and threaded for engagement with the screw threads of the nozzle.

5. An accessory for collapsible tubes having a comparatively rigid top and a projecting screw-threaded outlet nozzle, a cover shaped to fit the top, an arm pivoted to the cover and provided with a bearing loop, said arm being provided with a resilient loop between the point of its pivoted connection with the cover and said bearing loop, and a cap having a head and a body, the last-named being threaded for engagement with the screw threads of the nozzle and being mounted in said bearing loop to have turning movement therein.

6. An accessory for collapsible tubes having a comparatively rigid top and a projecting screw threaded outlet nozzle, said accessory comprising a cover shaped to fit the top, an arm pivoted at one end to the cover and provided with a bearing loop at the opposite end, said arm having an elongated resilient loop between its pivoted end and said bearing loop, providing for actuation of the loop relatively to the cover to move the bearing loop relatively thereto, and a cap threaded for engagement with the screw threads of the nozzle and mounted in said bearing loop to have turning movement therein.

7. An accessory comprising in combination with a collapsible tube having a comparatively rigid top with a bead flange and a projecting outlet nozzle, and leg members for the tube engaging with the bead flange, a cover shaped to fit the top, a cap for the nozzle, a device supporting the cap to the cover and adapted to be moved into a position in which the cap will be in adjoining coaxial relation to the nozzle, the cap being supported for independent movement with respect to the supporting device and relatively with respect to the cover, a flange on the cover engaging over the leg members, and means for securing the flange to the leg members.

8. In combination with a collapsible tube having a comparatively rigid top end and a projecting exteriorly threaded outlet nozzle, a cover shaped to overlie the top end of the tube and to fit about the nozzle, a holder attached to the cover for movement with respect thereto, a cap carried by the holder for rotary movement with respect to both the cover and the nozzle, said cap being threaded for engagement with the threads of the nozzle.

9. In combination, a resilient arm, a base at one end thereof for supporting said arm, a screw threaded cap for an outlet nozzle of a collapsible tube, means supporting the cap from the opposite end of the arm, including a positive guiding engagement which permits rotary movement of the cap while guiding the cap in an axial line to give the cap a vertical line movement in alignment with the nozzle, whereby to connect the cap to, and disconnect it from, the nozzle on a vertical line movement, and a member to which said base is attached, shaped to afford and maintain an engagement with conical end of the tube.

10. An accessory for a collapsible tube comprising in combination, an arm having one end engaged with a cover shaped to afford and maintain an engagement with the conical top of said tube, for retaining said arm in position, a cap adapted to be engaged with the screw threaded nozzle of said tube, means supporting the cap from the opposite end of the arm so as to permit the cap to be freely and bodily moved in vertical alignment with the nozzle a vertical distance sufficient for the connection of the cap to, and its disconnection from, the nozzle, said cap being screw-threaded for effecting threaded engagement with the nozzle of said tube.

11. An accessory for a collapsible tube comprising in combination, an arm, means associated with the tube for attaching and supporting said arm at its lower end, a screw-threaded cap for engagement with the nozzle of said tube, a threaded pin attached to said cap in vertical alignment with the

center of said cap, a threaded bearing at the upper portion of said arm in threaded engagement with said pin and adapted while permitting threaded movement of the pin in 5 the bearing to sustain the pin and hence the cap when the latter is disconnected from the nozzle of said tube.

In testimony that I claim the foregoing as my invention, I have signed my name hereto.
